UNITED STATES PATENT OFFICE

HARVEY HUBER ESLINGER, OF HARRISBURG, PENNSYLVANIA, ASSIGNOR OF ONE-FOURTH TO CARL HANSON, OF HARRISBURG, PENNSYLVANIA

SAFETY DEVICE FOR INTERNAL-COMBUSTION ENGINES

Application filed April 3, 1928. Serial No. 267,092.

This invention relates to electrical safety devices, and particularly to a protective circuit for internal combustion engines, the operation of which is responsive to some abnormal condition in the functioning of the engine for grounding a circuit upon which the normal operation of the engine depends, for instance, the ignition circuit, thereby automatically stopping the engine until the said untoward condition can be rectified.

One of the objects of the invention is the provision of a device of the class described which can readily be applied as an attachment to the electrical systems of automobiles now existing.

Another object of the invention is to provide a shunt circuit connected into the primary circuit system of the ignition system, whereby arcing at the interrupting element or elements is avoided and long life and reliability in the operation of the system assured.

Still another object of the invention is to provide positively operated auxiliary means for rendering the shunt circuit inactive, at times when it is desired to operate the engine notwithstanding the absence of certain conditions characteristic of the normal running state of the engine. For example, when the device is so designed that closing of the shunt circuit with consequent interruption of the ignition system, is responsive to low pressure in the lubrication system, it would be impossible to start the engine, since the oil pressure remains nil until the engine is started and the shunt circuit would consequently remain closed.

A further object of the invention is the provision of an auxiliary safety shunt circuit, with actuating devices, controlled as described by abnormal engine conditions, either of pressure or temperature or both, said circuit being connected into the primary ignition circuit at a point between the transformer and breaker points, at a part of the circuit operating with relatively low amperage.

Other objects of the invention will appear as the following description of a preferred embodiment thereof proceeds.

In the drawings in which similar charac-

ters of reference are used throughout to identify the same part,

Figure 1 is a diagrammatic view, partly in longitudinal section of the electrical ignition system of an internal combustion engine, showing the automatic interrupting circuit of the present invention together with mechanical embodiments of the several interrupting organs through which the system is operated.

Figure 2 is a view in perspective showing a modified feature of the invention in which the relief switch is combined with the choke rod associated with the fuel supplying mechanism of the engine.

Referring now in detail to the several figures the numeral 1 represents part of the engine cylinder block in longitudinal sections, the spark plug being represented at 2 and being in the secondary circuit 3 of a transformer coil 4, the primary circuit 5 of which includes a source of current 6 grounded as usual through the breaker points 6'.

The spark plug is of course, grounded in the usual manner, to the engine block and the primary winding of the coil is grounded as shown at 7.

An ignition switch 8 is intercalated in the primary circuit being preferably conveniently located upon the instrument board 9.

All that has been described up to this point is of conventional construction and arrangement and the present invention begins with the auxiliary shunt circuit, consisting of the single wire 9 which taps the primary ignition circuit at any desired point, for instance, at the binding screw 10 of the primary winding of the coil and leads to a ground upon the engine cylinder block, or any associated electrically connected part. The engine ground in this shunt circuit consists of a normally open switch or interrupter controlled either thermostatically or by fluid pressure so as to close upon a predetermined rise of the engine temperature or an abnormal pressure change in some pressure factor incident to the engine operation, such as a predetermined subnormal pressure value in the lubrication system.

In the present instance there are two in-

rupters in the shunt circuit, arranged in electrical parallelism and independently automatically operable to close the shunt circuit.

5 One of the interrupters comprises a thermostatic element 11 arranged to be within the influence of the heat of the cylinder block, preferably as shown, in direct metallic contact with the cylinder block through 10 a metallic base 12 secured thereupon, said thermostatic element carrying a movable contact 13 normally separated from an insulated contact 14 to which the shunt circuit wire 9 is connected. Upon a predetermined 15 excessive rise of the temperature of the cylinder block, as for example, when the cooling water or oil supply becomes depleted, the thermostatic element 11 which is in the form of a coil unrolls, bringing the contacts 13 and 20 14 together thus closing the shunt circuit and diverting the primary current from the coil 4 thus inhibiting the interrupting, functioning of the ignition circuit.

The fixed contact 14 is adjustable so that 25 the gap between the contacts may be varied in accordance with the degree of heat of the cylinder block at which it is desired to have the shunt circuit activated.

The other or alternative interrupting device, as shown, is pressure actuated, and communicates with the oil circulation system. This device may consist of a Bourdon tube 15 of electrically conductive substance arranged in spaced proximity to the insulated 30 adjustable fixed contact 16. The Bourdon tube being in metallic continuity with a conduit 20 of the lubrication system is thereby necessarily grounded. The fixed contact is connected by a branch wire 17 to the main 35 shunt circuit wire 9.

40 When the pressure in the lubrication system diminishes through lack of sufficient oil the Bourdon tube begins to reduce its degree of curvature, and finally, at a predetermined 45 low pressure value, it makes engagement with the fixed contact 16 thereby closing the shunt circuit.

It is obvious that either of these interrupting devices is capable alone of closing the 50 shunt circuit and thus interrupting the ignition system of this engine respectively in response to overheating of the engine or sub-pressure in the lubrication system. However, there is a peculiar advantage in the combined use of both these devices, in response to 55 lubrication conditions in the engine.

If the lubricant becomes fouled by sediment or diluted with gasoline, in either case impairing its viscosity and increasing its 60 friction between the lubricated parts, the temperature of the water will rise operating the thermostatic interrupter, although the pressure responsive interrupter will not be actuated since the pressure in the lubricating system remains normal. On the other

hand, should the oil supply become depleted while the engine is standing still, as through leakage, incalculable damage might be done before the temperature of the cooling water had raised to the point at which to operate the 70 thermostatic interrupter.

In this event, however, the pressure actuated interrupter would at once respond to the dearth of oil, closing the shunt circuit and stopping the engine.

75 It is of course realized that there is no pressure in the oil system until the engine has been started and that the use of a pressure responsive interrupter in the shunt circuit would by itself preclude the possibility of 80 starting the engine, and that therefore some means for temporarily breaking the shunt circuit must be provided at the time of starting so as to render the ignition system active. For this purpose, the invention makes 85 provision for a manually operable release switch 18, in the shunt circuit and preferably located on the instrument board 9. This switch when opened renders the shunt circuit inactive so that the ignition circuit can func- 90 tion in its normal manner.

95 One of the advantages of the invention flows from the fact that the shunt circuit is tapped from the primary ignition circuit instead of the secondary ignition circuit, as is usual in electrical safety systems as hitherto devised. By tapping the low tension circuit, arcing between the contacts of the interrupting devices is prevented, and the reliability in the operation of the interrupting devices, is thus assured. Otherwise, the high tension current would tend to jump the gaps between the interrupter contacts interfering with the regularity of the ignition during the normal running of the engine.

100 Furthermore, the shunt circuit is connected into the primary circuit at a point between the transformer coil and ground, this being a part of the primary circuit where the amperage is low, thereby assuring against arcing 110 at the contacts of the several switches.

105 In those types of internal combustion engines in which it is customary to manipulate a choke rod when starting, it is convenient to combine the two operations of pulling the 115 choke rod and operating the safety switch. This may be accomplished by such a construction as is shown in Figure 2, in which the movable element 19 of the safety switch is connected to the choke rod 21, so as to be movable therewith. An elastic or lost motion connection 22 is preferably provided between the choke rod and the movable switch element so as to provide a greater range of movement for operating the choke rod than is necessary in operating the switch.

120 While I have in the above description endeavored to disclose a preferred and practical form of my invention it is to be understood that the principle of the invention may 125

be exemplified in other forms and arrangements of parts, without departing from the spirit and scope of the appended claim.

Having thus described the invention, what is claimed is:

10 In combination, in an internal combustion engine, an ignition system comprising primary and secondary circuits, a normally open circuit in shunt with the primary circuit of said ignition system, and normally open circuit closing means in said shunt circuit responsive to an abnormal condition of said engine for closing said shunt circuit to interrupt the normal functioning of said ignition system, a series connected switch in said shunt circuit and mixture regulating means, manipulable at starting the engine, with which said switch is interconnected, for simultaneous opening of said switch with the manipulation of said means.

20 In testimony whereof I affix my signature.

HARVEY HUBER ESLINGER.
